APPARATUS FOR THE LYE TREATMENT
AND WASHING OF CLOTHES

Cyprien Edouard Paul Julien, Paris, France

Application January 13, 1927, Serial No. 160,984,
and in France January 13, 1926

3 Claims. (Cl. 68—18)

The present invention relates to an apparatus for the lye treatment and the washing of clothes.

The known washing machines usually comprise a rotatable cylindrical receptacle provided with perforated walls, into which the clothes to be washed are stowed with greater or less pressure, and the said cylinder is rotated in a continuous or intermittent manner so that the clothes will be caused to fall or to strike repeatedly against the walls of the cylinder or against bosses by which the lye bath will be enabled to penetrate into the interior of the clothes. In other devices, the lye is also made to enter the clothes for washing purposes but herein the solution is drawn or forced through a mass of clothes of greater or less thickness which is contained in a receptacle. However, with all such apparatus the solution will not readily penetrate into the clothes by reason of the compact mass which it is obliged to traverse, and these devices, in order to secure an effective action, must therefore exercise a relatively violent mechanical action upon the clothes by which they will be subject to a certain damage.

My said invention obviates all such defects, and for this purpose the clothes which are to be washed or lye-treated are subjected to immersions in the bath and are allowed to stream or drip, in a successive manner, this being optionally accompanied by a slight friction of the articles upon one another, the articles being preferably stretched or spread out in thin layers during all such operations, and they will be thus subjected without shocks or pressure to the chemical action of the lye bath and then to the mechanical action or friction produced by the streaming or flowing of the liquid over or from the articles. Since the clothes are thus brought into contact with the liquids upon the maximum extent of surface, and without compression, the chemical actions which constitute the saponification will take place in the most approved conditions. The streaming of the liquid will facilitate the physical action of the slight friction to the maximum degree, so as to remove all coagulated or insoluble substances from the textile fabric.

In the embodiment illustrated a rotatable device such as a horizontal drum of open work construction which is provided with cross bars or like members, upon which are disposed the articles to be washed, so that they will be drawn forward with the said bars during the rotation of the drum and will thus be immersed successively in the lye bath which is contained in a suitable receptacle. The arrangement may be such that when the articles are once placed in position in

the apparatus they may be subjected therein—and without any further handling—to all the successive operation which may be required for the lye treatment and the washing, such as preliminary washing, lye treatment, washing, chlorine water treatment, rinsing, centrifugal or like drying, and optionally a complete drying.

For such drying, I provide for the production of a current of air for drying purposes by the rotation of the washing apparatus itself, said device comprising a rotary pump which is mounted directly or indirectly upon the shaft of the rotatable drum, in combination with a conduit for heating the air which is optionally removable and ends in the interior of the tank, so as to assure within the said tank a circulation of air heated to the proper temperature for furthering or effecting the drying of the clothes contained in the drum.

In the appended diagrammatic drawings which show by way of example an embodiment of the said invention:

Figs. 1 and 2 are respectively a side and an end view of a drum forming part of the lye treating apparatus,

Figs. 3 and 4 are respectively a side and an end view of the entire lye treating apparatus,

Fig. 5 is a vertical axial section of the machine with the cover removed showing a slightly different form,

Fig. 6 is an end view of the form shown in Fig. 5,

Fig. 7 is a diagrammatic view showing the use of a reticulated cover around the clothes on the rods, the structure being modified to the extent of illustrating several additional rods.

The element which serves to contain the pieces of clothing to be washed consists of a drum in the form of a squirrel cage-like structure comprising two heads 1—2 which are connected together by the transverse bars or like members 3, 4, 5, 6, (Fig. 2) in the present example, the said bars being disposed in pairs at the respective ends of a given diameter of the head, but they may obviously be otherwise arranged and any desired number used provided that they are spaced at distances sufficiently great to enable manual reaching between the bars for the looping of clothes thereupon so that they hang down inside. The drum thus formed is provided with stub shafts 7, 8 disposed in bearings which are formed at the ends of the supports 9, 10 (Figs. 3 and 4), which supports also serve to maintain the tank 11 which may have a semi-cylindrical shape and contains the lye solution, said tank is pro-

vided with a cover which is preferably hinged. Upon one of the stub shafts of the drum (for instance 8) is mounted an actuating element which in the present example consists of a hand crank 13. The provision of the two stub shafts for the support of the drum, instead of a single shaft extending axially through the drum, establishes an internally untrammelled drum in which the clothes are freely raised and dipped during drum rotation without any interference whatsoever.

10 The operation is as follows:

The clothes, which may be preliminarily washed or soaked in tepid water in the apparatus, are hung upon each bar as upon a clothes line, beginning with the top bar and bringing each bar successively in the top position, and if necessary, several pieces of clothing can be placed in the superposed position upon the bar. The heater which may be of any character desired is so regulated as to produce or to maintain the temperature which may be successively required for the liquid, and the said drum is suitably rotated for the requisite length, of time, according to the nature of the operation and the 25 quality or the condition of the clothes. Each time that a bar is made to descend through the lye bath, the clothes which it carries will spread out in the liquid and will be immersed in the bath and subjected to the slight friction of one 30 part of the textile fabric upon other parts by which the fibres will be brought against one another, and the fabric will be impregnated with the liquid in all its parts; this will continue until the bar rises to the diametrically opposite point. 35 Since the clothes are drawn through the bath at a suitable speed, they will draw up a certain quantity of liquid and this will fall by gravity and will stream upon or through the fabric, so that the yarn composing it will be thus washed.

40 After the clothes have been thus subjected to the lye treatment, the lye bath can be replaced by other baths which may be successively placed in the tank. After the clothes are rinsed and all the additional operations completed, the tank 45 being emptied and the clothes being still in place, the drum may be rotated at a greater speed than before in order to effect a certain centrifugal drying, and even a more or less complete drying if the heating device still continues to heat the 50 air which is contained in or is blown through the apparatus.

To avoid all contact between the clothes and the internal walls of said tank, I interpose between the tank and the drum, and preferably maintain upon the latter, a peripheral element which may consist of a large mesh or reticulated cover 55 (Fig. 7). This cover is applied to the drum in an encompassing position to bear down on the looped portions of the clothes and grip them so as to hold them. The ends of the cover are fastened together by any suitable means 20^a (Fig. 7), as for example, a hook. It will be understood that one of the purposes of the reticulated cover is to keep the clothes astride of the bars, the 60 spacing of these bars having been touched upon previously.

In the form shown in Figs. 5 and 6 the rotatable drum of the washing machine consisting of the end heads 1-2 which are connected together by 70 the cross bars (or like members) 3 is supported by means of the stub shafts 7-8 whereof at least one of which, 7, is hollow, upon the supports 9-10. In this form tank 11 is mounted in the body of the heater 14 which may be supplied with 75 any suitable fuel and is adapted to heat the bot-

tom of the tank 11 either directly or with the interposition of a register 15 (Fig. 6) for regulating or cutting off the heat.

Within the said heater is disposed a spiral or worm tube 16 which is connected at one end with the delivery end of a pump 17 which is preferably actuated by the hand crank 13 of the drum. The said pump (or blower) may be of the centrifugal type, and the rotor may be mounted directly upon the corresponding journal 8, but it is preferably connected with the said journal 8 by suitable speed-increasing transmission means. The other end of the said worm tube 16 is connected with the hollow journal 7 of the drum 2.

80 The operation of the form shown in Figs 5 and 6 is as follows:

The clothes are suspended and spread out within the squirrel cage-like structure formed by the open work drum 1-3 and when thus disposed they are subjected to the washing operations as disclosed in Figs. 1 to 4. The clothes are then given a certain centrifugal treatment after the tank has been emptied. The heater being maintained in the active condition and the drum set in rotation, the air delivered by the pump 17 95 through the worm 16 will reach the said tank at a high temperature; the cover of the said tank (not shown) is placed upon the tank. The air in the tank is thus gradually heated, and it will heat the moisture contained in the clothes and 100 convert it into vapour, thus sterilizing the clothes when in a clean condition. The drum is rotated slowly, or at stated intervals, so that each bar 3 together with the clothes will proceed, together with the clothes which it draws along with it, to 110 a point within a short distance from the bottom of the tank which is heated to the maximum temperature; but the clothes are not allowed to make contact with the bottom whereby they would be burned, due to the reticulated cover 20 115 which normally surrounds the said drum. To prevent an excessive temperature in the dry tank, I preferably interpose the register 15 so as to prevent direct contact between the flames of the burner and the bottom of the tank 11; said register 120 may consist of perforated sheet metal pieces, whose perforations can be optionally brought into coincidence.

In this manner the clothes are dried by the simultaneous action of the hot air in the tank 125 which becomes saturated with the moisture withdrawn from the clothes, and of the current of hot and dry air supplied by the blower to the tank, after passing through the worm tube 16. This air becomes charged with the humidity of the 130 tank and draws it out of the latter through suitable apertures in the tank or its cover.

The tubular arrangement 16 of the blowing device may assume all shapes and sizes and may optionally form part of the heater or the tank. 135 It may be constructed, in particular, by disposing a hollow jacket around the burner, either totally or partially, said jacket being connected at one end with the blower or pump 17 and at the other end with the hollow journal 7.

The heater or furnace 14 and the tank 11 may be constructed separately or in combination and may have any shape or size. The drying air may be optionally heated by any suitable heater or by any source of heat.

140 This invention is applicable to all forms of washing drums, stationary or portable, which are adapted for use with all types of tanks or heating devices. The frame upon which the device consisting of the tank and the drum is disposed 150

may be of any suitable form, and I am thus enabled to construct washing apparatus of all sizes, whether stationary or mounted upon rollers.

What I claim is:

- 5 1. In a washing machine, means providing an internally untrammelled drum in which the clothes are freely raised and dipped with respect to the liquid upon rotation of the drum, said means comprising bars over which the clothes are 10 looped to hang down inside, spaced heads to which the ends of the bars are connected to complete the drum, a stub shaft on each head, and means tightly encompassing the drum to grip the clothes against the bars.
- 15 2. In a washing machine, means providing an internally untrammelled drum in which the clothes are freely raised and dipped with respect to the liquid upon rotation of the drum, said means comprising bars over which the clothes are 20 means to bear down on the clothes at the bars to keep the clothes from slipping.

looped to hang down inside, spaced heads to which the ends of the bars are connected to complete the drum, a stub shaft on each head, and means tightly encompassing the drum to grip the clothes against the bars.

3. In a washing machine, means providing an internally untrammelled drum in which the clothes are freely raised and dipped with respect to the liquid upon rotation of the drum, said means comprising bars over which the clothes are looped to hang down inside, spaced heads to which the ends of the bars are connected to complete the drum, a stub shaft on each head, reticulated means encompassing the drum to enclose those portions of the clothes looped over the bars, and means to lock the ends of the reticulated means together thus causing said means to tightly grip said looped portions.
